UNITED STATES PATENT OFFICE

101,582

DESIGN FOR A TEXTILE FABRIC OR SIMILAR ARTICLE OF MANUFACTURE

John F. Gaul, Jr., Clifton, N. J., assignor to Botany Worsted Mills, Passaic, N. J., a corporation of New Jersey

Application June 19, 1936, Serial No. 63,395

Term of patent 14 years

To all whom it may concern:

Be it known that I, John F. Gaul, Jr., a citizen of the United States of America, residing at No. 1110 Van Houten Avenue, in the town of Clifton, State of New Jersey, have invented a new, original, and ornamental Design for a Textile Fabric or Similar Article of Manufacture, of which the following is a specification, reference being had to the accompanying drawing, forming a part thereof, and showing a face view of a piece of textile fabric embodying my design.

The characteristic feature of the present design resides in a plain base fabric which is loosely

woven, resulting in a rough or crepe-like appearance, and a series of stripes composed of two vertical threads embodied in the background and having nubs disposed at substantially regular intervals over the surface of the fabric, the nubs being composed of lustrous threads of substantially the same color as the color of the background as shown.

I claim:

The ornamental design for a textile fabric or similar article of manufacture substantially as shown and described.

JOHN F. GAUL, JR.
